UNITED STATES PATENT OFFICE.

WILLIAM F. LAUTENSCHLAGER, OF CINCINNATI, OHIO, ASSIGNOR TO LORENZ MUTHER,
OF NEWTON, MASSACHUSETTS.

SKIVING-MACHINE.

1,210,815.

Specification of Letters Patent. Patented Jan. 2, 1917.

Application filed March 9, 1914. Serial No. 823,274.

To all whom it may concern:

Be it known that I, WILLIAM F. LAUTENSCHLAGER, a citizen of the United States residing in Cincinnati, county of Hamilton, 5 State of Ohio, have invented certain new and useful Improvements in Skiving-Machines, of which the following is a specification, reference being had to the drawings accompanying the same and forming a part thereof.

10 My invention relates to improvements in skiving machines of that class wherein a rotating cutting knife is employed, together with a feed-wheel or roll for supporting 15 and feeding the material while it is being skived.

The objects of my invention are to so construct the feed-wheel or roll that it will automatically accommodate itself to varying 20 thicknesses of material and present the material to the rotating cutter at any desired angle.

A further object of my invention is to provide adjustable spring-controlled means 25 for normally retaining the feed-wheel or roll with its axis in line with the axis of its rotation, together with means for rigidly retaining the feed-wheel or roll with its axis in line with its axis of rotation when it is 30 found desirable so to do.

My improved feed-wheel or roll may be applied to any skiving machine wherein there is employed a rotating cutter. It is shown as applied to the skiving machine 35 illustrated in Letters Patent of the United States No. 1,091,753, of March 31, 1914.

In the drawings Figure 1 is a front elevation of a section of a skiving machine 40 wherein my improved feed-wheel or roll is embodied; Fig. 2 is a sectional side elevation of my improved feed-wheel or roll illustrating it with its axis held in line with its axial or rotation by a yielding spring and an adjusting nut; Fig. 3 is an enlarged sectional side elevation of my improved feed- 45 wheel or roll, illustrating it as it would appear with its axis deflected to an angle to its axis of rotation; Fig. 4 is an elevation taken through line 4-4, Fig. 1, viewed 50 from the right hand end.

In the drawings, 1 represents the shaft of a skiving machine upon which the disk 2 is rigidly mounted and secured against rotation by a binding-screw 3. This shaft 55 1 is provided with a hole 4 in its end, ar-

ranged to receive the pin 5 which is secured in the inner end of the bearing 6, the bearing 6 being provided with a projecting rim or head 7, somewhat thinner than the space 8 in the disk 2 in which the head 7 is mounted. The edges 9, 9, of the projecting head 7 have a curvature conforming to a circle developed from a point located at the axis of the bearing 6 so that when its axis is at an angle to the axis of the shaft 1, 60 as shown in Fig. 3, the head 7 will exactly fill the bore in the disk 2. The outer end of the bearing 6 is threaded to receive the adjusting nut 10, the threads extending in far enough so that the adjusting nut 10 65 may be turned inwardly to contact with the collar 11 and force its inner end against the disk 12, pressing the disk 12 against the disks 13, 13, 13, 13, and they in turn against the face 14 of the disk 2, but with the inner 70 face 15 of the projecting head 10 drawn tightly against the surface 16 of the space 8 in the disk 2. This rigidly binds the disks 12 and 13, and the bearing 6, against the disk 2 and rigidly holds all said parts 75 so that their axes are in a right line with the axis of the shaft 1.

The disk 2 has secured to it the pin 17 which projects outwardly and into holes 18, 18, etc., in the disks 13 and the disk 12. 80 The purpose of the pin 17 is to drive the disks 12 and 13, or rotate them from the shaft 1. The holes 18 are considerably larger than the diameter of the pin 17 so that the disks may be deflected so their axes 85 will be inclined to an angle with the axis of the shaft 1, as shown in Fig. 3, the purpose of which will be more fully described 90 hereinafter.

There is a spiral spring 19 surrounding the 95 collar 11, its outer end bearing against the adjusting nut 10 and its inner end against the outer face of the disk 12. The purpose of the spring 19 is to normally hold the bearing 6 and the disks 12 and 13, etc., 100 with their axes in alinement with their axes of rotation, or in a right line with the axis of the shaft 1 through the tension of the spring exerted against the inner face of the clamping nut 10 and the outer face 105 of the disk 12, pushing the disk 12 and the disks 13, etc., against the face of the disk 2, and drawing the surface 15 of the head 7 against the surface 16 of the contracted portion of the hole or space 8. The tension 110

of the spring 19 is adjusted by turning the clamping and adjusting nut 10 inwardly or outwardly upon the threaded portion of the bearing 6.

5 In skiving leather for shoe uppers, vamps, etc., where it is of somewhat uneven thickness; *i. e.*, where the different uppers and vamps vary from each other in thickness, and where different portions of a vamp or 10 upper vary in thickness, it is desirable when skiving the edge to vary the slope or angle at which the strip skived off is cut, according as the material varies in thickness. To skive the material properly, it is desirable 15 to keep the edge of the material at a uniform thickness and not run the skiving cut back too far upon the body of the material. To attain this object it has heretofore been necessary to change the angle at which the 20 rotating cutter stands with relation to the supporting surface of the feed-wheel or roll, which change is not desirable because of the necessity of stopping the machine to do it properly and the consequent time it takes 25 to make such change. Another way of meeting the difficulties arising from varying thicknesses of the material being skived is to provide for varying the angle of the supporting wheel as a whole, but such form 30 of adjustment has been found undesirable for the reason that it tends to vary the thickness of the edge of the material after it is skived. In my improved device I employ a feed-wheel or roll made up of a plurality of disks mounted upon a bearing and 35 so arranged that the several disks may be deflected to varying degrees from nothing at the supporting disk to the full desired amount of the deflection at the outermost disk, as is illustrated in Fig. 3.

In Fig. 1 there is illustrated a gage 20 against which the edge of the material to be skived is guided, and which gage determines the width of skive, the gage having 45 an extending portion 21 extending over the feed-wheel made up of the disks 12 and 13, serving to hold the material down in place at the point where the skiving cut takes place. In conjunction with the guide 21 50 I provide a rotating feed-wheel 22 which bears upon the leather and holds it against the flange 23 of the disk 12.

In practice, the feed-disk 22 is mounted upon the shaft 24 and is rotated thereby, the shaft 24 having an adjusting collar 25 adjustably secured to it by the binding-screw 26 so that the upward movement of the feed-disk 22 can be limited and its lower surface is set a distance apart from the flange 23 approximately equal to the thinnest piece of leather which is to be skived; then if the adjusting nut 10 is adjusted outwardly as shown in Fig. 2 so as to leave space between it and the collar 11, the disks 65 12 and 13 and the pivot 6 are held in aline-

ment by the tension of the spring 19, the tension of the spring 19 being sufficient to maintain feeding contact between the flange 23 and the lower side of the feed-disk 22. Whenever a thick spot in the leather comes 70 between the disk 22 and the flange 23 the disks 12 and 13 will be deflected downward an amount equal to the increase in thickness, assuming the position shown in Fig. 3, and as the thick part of the leather passes 75 through and the thin part is reached, the spring 19 gradually causes the disks to approach their normal position with their axes in line, or more nearly in line with the axis of rotation of the feed-wheel and shaft 1. 80 It is thus seen that the feed-roll automatically accommodates itself through the tension of the spring 19 to the varying thicknesses of material passing between the feed-disk 22 and the flange 23 of the feed-wheel. 85

It will be noted that the innermost of the disks 13, *i. e.*, the one that lies against the disk 2 is deflected very slightly, as shown in Fig. 3, and the axis of each succeeding disk, including the outer one 12, stands at a greater angle of deflection, the angle depending on the thickness of the material passing between the flange 23 and the feed-disk 22, so that the variation of thickness at the edge of the material after the skiving 90 cut has taken place is not appreciable, but the variation in the angle of cut may be quite considerable in a piece of material extra thick, the angle varying as the material passes through from the thickest part 95 to that portion having a normal thickness. Where the material runs uniform in thickness the adjusting nut 10 may be screwed inwardly to bind the collar 11 and the disks 12 and 13 firmly against the disk 2 and prevent any deflection. 100

When the machine is used for skiving heavy material, such as heavy calf, the feed-disk 22, as stated before, is adjusted so that its upward movement may be limited by 110 means of the collar 25 to the thinnest piece of material. When the skiving machine is used for skiving very thin material, like vici kid, another adjustment of the feed-disk 22 is required; *i. e.*, the collar 25 is so 115 adjusted on the shaft 24 that the thinnest piece of vici kid will pass between its end surface and the flange 23 without deflection of the feed-wheel, the spring 19 permitting such deflection as will accommodate the 120 varying thicknesses of the different pieces of vici kid and the varying thicknesses in each individual piece.

I do not wish to confine myself to the exact form of the parts as illustrated herein, or the manner in which the feeding wheel or roll is mounted on the skiving machine, as the form and method of mounting may be varied without departing from the spirit 125 of my invention. 130

What I claim is—

1. In a skiving machine, the combination with a cutting knife of a feed-wheel for feeding and supporting the material, which feed-wheel consists of a disk mounted on a rotatable shaft, said rotatable shaft, a rotatable bearing movably mounted in said disk, a plurality of rotatable disks yieldingly mounted on said rotatable bearing, a spring for normally retaining said rotatable bearing in alinement with the rotatable shaft, and an adjusting nut for adjusting the tension of said spring.
2. A feed-wheel for skiving machines, comprising a disk having a fixed axis of rotation mounted on a rotatable shaft, said rotatable shaft, a rotatable bearing having one of its ends mounted in said disk in such manner that its axis of rotation may be varied with relation to the axis of rotation of said rotatable shaft, a plurality of disks yieldingly mounted on said bearing, means for causing said plurality of disks to rotate with the disk having the fixed axis of

rotation, spring-controlled means for normally holding said plurality of rotatable disks with their axes of rotation in alinement with the axis of rotation of the rotatable shaft, and means for varying the tension of said spring.

3. A feed-wheel for skiving machines for supporting and feeding the material, consisting of a plurality of rotatable disks, and yielding means to permit the axes of rotation of a plurality of said disks to be automatically varied with relation to the cutting plane of a cutting knife, and means that may be adjusted to rigidly hold said disks with their axes of rotation in alinement with each other.

In testimony whereof, I have hereunto set my hand, in the presence of two subscribing witnesses, this the 7th day of March, A. D. 1914.
